Int. Cl. D10—01

U.S. Cl. D42—7

Fig. 1.

Fig. 2.

Fig. 3.

FIG. 1 is a front elevational view of a clock showing my new design;

FIG. 2 is a side elevational view thereof;

FIG. 3 is a sectional view thereof taken along the section line 3—3 of FIG. 1.

The characteristic feature of my design resides in the combination of the specific ornamental band and the clock face and hands on the clock housing as shown.

I claim:

The ornamental design for a clock, as shown and described.
